ODORIZING APPARATUS AND METHOD FOR
GAS LINES

Frederic A. Hough, Pasadena, Calif.

Application September 22, 1931, Serial No. 564,456

10 Claims. (Cl. 48—195)

This invention relates to apparatus and a method for introducing an odorant into a line in which a fluid is flowing, for example, a gas line.

Many deaths have resulted from the fact that 5 illuminating gas or gas for domestic or industrial use, leaks out in such a way as to poison the air, or cause an explosive mixture. For this reason, it is desirable to introduce into gas, an odorant, which, if the gas escapes, will be so disagreeable as 10 to call attention to the leak immediately.

The general object of this invention is to produce a simple apparatus and method for introducing an odorant or other substance into a gas line.

15 A further object of the invention is to provide means for feeding small quantities of the odorant into a line at a rate approximately proportional to the rate of gas flow, and to provide means for controlling the rate of feed of the odorant through 20 the agency of a differential pressure, and/or static pressure in the line before, and at the point where the odorant is being introduced; also to provide means for automatically increasing the feed of the odorant if the quantity of the gas flowing in 25 the line increases.

In the practice of the invention the apparatus preferably includes a feeding device or chamber in which a small quantity of the odorant is maintained and fed forward through a regulated connection into the pipe line, and one of the objects 30 of the invention is to provide a sight feed device cooperating with the feeding container in such a way as to enable the amount of feed to be observed and measured from time to time, if desired; and also to connect the sight feed device 35 in such relation to the feeding container as will enable it to cooperate in maintaining a substantially constant level for the liquid in the feeding container.

40 A further object of the invention is to provide an efficient method for effecting the continuous and automatic introduction of an odorant or other substance into a gas line, utilizing the differential and/or static pressure established in the line to 45 maintain the continuous operation of the apparatus and method.

Further objects of the invention will appear hereinafter.

As regards the apparatus, the invention consists in the novel parts and combinations of parts 50 to be described hereinafter, all of which contribute to produce an efficient odorizing apparatus and method for gas lines.

The invention also resides in the steps and 55 combination of steps to be described hereinafter,

all of which cooperate to produce an effective method for introducing a substance into a gas line.

A preferred embodiment of the invention is described in the following specification, while the 5 broad scope of the invention is pointed out in the appended claims.

In the drawings:—

Figure 1 is a diagrammatic view, illustrating apparatus embodying the invention and by which 10 my method can be practiced, and representing the apparatus connected to a pipe line, certain parts being broken away.

Figure 2 is a vertical section through a feed 15 container for the liquid which is fed into the line, and particularly illustrating the preferred construction of the same for maintaining a liquid in the container under pressure and for maintaining a substantially constant level of the liquid in the container.

Figure 3 is a similar vertical section through 20 another embodiment of the feed container, which may be employed in the apparatus shown in Figure 1 instead of the feed device illustrated in Figure 2.

Figure 4 is a vertical section through a pressure control valve, illustrated in Figure 1, and particularly illustrating the construction of this valve which enables the amount of flow through the valve to be regulated by the pressure maintained in the feed device.

In practicing the invention, I maintain a feed 30 chamber for the odorant to which the odorant is supplied in liquid form. I subject the surface of this liquid in the feed device to a pressure equal 35 to that before the restricting device in the gas line to enable the odorant to be introduced into the gas flowing in the line.

Means is provided for restricting the flow in 40 the line. For this purpose, I prefer to employ an orifice disc having an orifice through it of smaller diameter than the pipe line, thereby developing a zone of differential static pressure in the line; that is to say, a differential pressure is developed 45 in the gas in front of, and beyond, the orifice.

In addition to this, I provide a feed device containing a quantity of the liquid, and in this feed device the liquid is subjected to a pressure corresponding to the static pressure in the line before the orifice disc. The outlet of the feed device is connected to the line beyond the restricting means or orifice disc, and this connection preferably includes a pressure controlled valve that automatically increases the flow of the odorant if the static pressure rises in the line. This con- 55

nection also preferably includes a sight feed device having a sight opening at which the rate of feed may be observed, and it is also preferable to construct the sight feed device in such a way that, if desired, the amount of odorant being delivered by the sight feed device can be collected for a short period of time without disturbing the rate of flow of liquid to ascertain positively the rate of feeding forward of the odorant into the line.

The apparatus also preferably includes an elevated reservoir or container for a supply bath of the odorant located at a higher level than the feed device, so that a gravity feed takes place from the reservoir to the feed device. The amount of this feed is controlled by an automatic device, such as a float in the feed device. In order to develop pressure sufficient to enable the liquid fed into the feeding device, to overcome the pressure in the feed device, the liquid in the reservoir is subjected to a pressure corresponding to the pressure in the line before the restricting means. For this purpose, I connect both the feed device and the reservoir to the gas line at a point before the restricting means, thereby insuring that, at all times, the static pressure of this line at this point is maintained in both the reservoir and the feed device.

One of the features of the invention consists in locating the sight feed device, so that its delivery outlet is at the normal level of the liquid in the feed device, thereby insuring that the bath of liquid in the feed device will not drain out of the feed device when there is no flow of gas to be odorized.

Although it is possible to introduce small quantities of a liquid odorant directly into the line beyond the restricting means, I prefer to provide a fogging apparatus including a vaporizer in which the odorant is converted into a vapor that passes readily into the gas line so as to diffuse itself quickly throughout the gas flowing in the line.

Referring more particularly to the parts, 1a represents a pipe leading from a gas supply and connected through a valve V with a pipe line comprising two sections 1 and 2, between which restricting means 3 is provided, said restricting means preferably consisting of an orifice disc 4 having an orifice of reduced diameter, thereby operating to produce a differential pressure zone in the sections 1 and 2 of the line. The direction of flow of the gas is indicated by the arrows. The apparatus includes a feed device 5 (see Figure 2) with a restricted flow opening for the odorant. This feed device preferably has a pressure chamber 6 in its upper part and carries a regulating bath 7 of a liquid, such as an odorant, which is to be introduced into the pipe line. The interior of this feed device is connected by pipe connections 8, 9 and 10 with the section 1 of the pipe line at a point before the restricting means 3, although, if desired, any suitable means may be provided for maintaining a pressure in the chamber 6 corresponding to the static pressure in the section 1 of the pipe line. The pipe connection 8 is provided with a suitable valve 11, and another valve 12 may be provided in the connection 10 for controlling flow of the gas into this feed device. The feed device is provided with an outlet 13, which is preferably elevated above the bottom 14 of the feed device and is at the normal level of the bath 7, which level is indicated by the line 15. This outlet 13 connects by a duct 13a to the chamber carrying the bath

7 below the level of this bath. This duct maintains contact between the bath 7 and the outlet 13 even if the level of the bath falls considerably. Somewhere in the line of flow from the feed device, I prefer to provide means for restricting the flow so as to insure that the odorant will be fed forward in small quantities.

For this purpose, I prefer to provide an orifice disc 16 associated with the outlet 13 and having a small orifice 17 through which the liquid passes downwardly into a connection 18 that leads to the section 2 of the pipe line. In the connection from this outlet 13 to the pipe line, I prefer to include means for indicating the rate of flow of the odorant and this is preferably in the form of a sight feed device 19 (see Figure 1) connected to the pipe connection 18 and having a delivery outlet 20 opposite a window 21 of glass or similar material at which the drops or stream passing from the outlet 20 can be observed, and this delivery outlet 20 is preferably at or above the normal level 15 of the bath 7 in the feed device. This insures that when the apparatus is standing idle the liquid in the feed device will not drain out of it and will be preferably maintained at all times above the level of the outlet ports at 13.

In order to enable the rate of feed to be accurately measured when desired at the sight feed device, I prefer to provide a calibrated chamber 22 below the window 21 and into which the liquid passes. Below this calibrated chamber, a valve 23 is placed. By closing this valve 23, the quantity of liquid accumulated in the gauge 22 can be measured for a given time, and this quantity will, of course, indicate the amount of odorant that is passing into the line in this measured time.

A by-pass pipe 24 is provided around the calibrated chamber 22 including a valve 25. This valve 25 would normally be open, so that the closing of valve 23 will not affect pressure conditions in sight feed device 19. The liquid drips past the upper connection to this by-pass 24.

If desired, the liquid that passes the valve 23 may be passed directly into the low pressure side 2 of the line, but I prefer to vaporize this liquid and pass it into the line in the form of a fog or vapor. For this purpose, the valve 23 is preferably connected to a pipe connection 26 that connects to a coil 27 disposed around a central drum 28 within the vaporizer, the lower end 29 of the coil being set in the wall of this drum so as to deliver the liquid or vapors of the liquid into the interior of the drum. The drum is enclosed in a casing 30 having an upper head 31 provided with an outlet connection 32 leading from the interior of the drum for carrying the vapors off from the drum and delivering the same through the side of the line section 2 at the point 33. This pipe connection may be provided with a suitable valve 34. The coil 27 is heated in any manner desired, but preferably by means of a gas burner 35 supplied with gas through a valve 36 and passing down through a pipe connection 37 from a thermostatic valve 38, the opening of which is regulated by means of a thermostat 39 passing down into the interior of the drum from the upper head 31. This valve 38 may be supplied with gas from any suitable source, but, if desired, this may be accomplished by providing a pipe connection 40 leading off from the section 2 of the pipe line beyond a second valve V', and this pipe connection 40 may be provided with a suitable valve 41 and an automatic pressure regulator 42 for reducing the pres-

sure of the gas sufficiently to enable it to be burned in a satisfactory manner at the burner 35. In the pipe 40 beyond the regulator 42 a valve 43 should be provided.

5 The gases of combustion from the burner pass out through a flue 44 that passes out through a jacket 45 that surrounds the coil 27.

10 Referring again to the feed device 5, in order to maintain a substantially constant level for the bath 7 (see Fig. 2), I provide the feed device with an automatically controlled valve 46. This valve is preferably of a needle valve type, the stem of the valve being disposed in a vertical position and held against its seat by a float 47 15 pivotally mounted at 48 on the valve casing and formed with a shoulder 49 that engages the lower end of the valve stem. This float 47 may be made of sheet metal with a vent tube 50 extending from a chamber within it to an elevated point in the chamber 6 to equalize pressure on the interior and exterior of the float and prevent its being crushed by external pressure.

20 The valve 46 is supplied with the odorant through a pipe connection 51, which may deliver 25 into a screen chamber 52 in the covering of the feed device and which is provided with a screen 53. This screen is accessible by reason of a removable plug 54 located above it.

25 A suitable source of supply is maintained for 30 supplying liquid to the pipe connection 51, and this source of supply should be maintained under pressure corresponding to the pressure existing in the line section 1. For this purpose, I prefer to employ an elevated closed reservoir 55, the side of which is provided with a sight gauge 56 enabling the operator of the apparatus to maintain a sufficient supply bath of the liquid within the reservoir. The surface of the liquid in this reservoir is subjected to the line pressure 40 in the section 1 of the line. Consequently, the space in this reservoir above the liquid level constitutes a closed gas chamber. For this purpose, the pipe 9 is extended upwardly through a pipe connection 57 that is connected through the upper side of the reservoir. The reservoir may be supplied with liquid from its underside through a connection 58 connecting to a supply line 59 and provided with two valves 60 and 61 on each side of the connection 58. By closing the valve 60 and opening valve 61, liquid can flow into the reservoir, it being understood that at this time a drain valve 62 would be closed.

45 The pipe connection 59 leads over past the valve 60 and connects to the pipe 51 already described.

50 It will be evident that with the apparatus described above, a pressure will always be maintained in the feed device 5 corresponding to the pressure in the line section 1 and consequently 55 when there is a flow of gas through line 1, a differential of pressure will exist capable of feeding forward the odorant through the fogging apparatus and into the line section 2 at the point 33. However, in order to compensate for changes 60 in the static pressure in the pipe section 1, for example, where a rise in the pressure occasions an increased flow of gas past the point where the odorant is being injected into the line, I provide 65 compensating means for increasing the delivery 60 of odorant to the line. For this purpose, in the pipe connection 18, and preferably between the feed device 5 and the sight feed 19, I provide a pressure controlled valve 63 (see Figs. 1 and 4). This valve is formed with a pressure chamber 64, 70 to which the liquid is admitted from the feed

device 5, and this chamber 64 is connected with the interior of a bellows 65 extending up in the valve bonnet 66. The upper head 67 of the bellows carries a valve stem 68 having a tapered neck 69 that moves to and fro in an orifice 70, accordingly as it is regulated by the elongation or contraction of the bellows 65, under the changing pressure. In Figure 4, this valve is shown at rest, at which time there is no effective opening in the orifice 70. Below the orifice 70 the valve has a delivery chamber 71, the outlet of which connects to the sight feed 19.

75 The bellows 65 can be set for different pressures through the agency of an adjusting screw 72, against which a spring 73 thrusts, the lower 15 end of the spring seating on the upper head 67 of the bellows.

80 In Figure 3, I illustrate another embodiment of a feed device, which, if desired, can be employed instead of the feed device 5. In this embodiment of the feed device a ball float 74 is provided, which is guided to rise and fall in a substantially vertical direction, the upper end of the ball operating through a system of levers 75 to control a needle valve 76 that controls the 25 admission of the odorant from the supply. The pressure in the interior of this feed device is maintained by a pipe connection 77 corresponding to the pipe 10 of Figure 1.

85 The side of the casing forms a sight feed provided with a window 78, back of which a gauge chamber 79 is formed, which is connected through ports 80 and 81 with the interior of the feed device.

90 If the absolute pressure within the gas line 35 is below atmospheric pressure, it will not be necessary to provide a high pressure in the feed device 5, nor in the reservoir 55. Under these circumstances, it will merely be necessary to have a pressure in them slightly higher than the absolute 40 in the gas line, for example, the pressure equal to atmospheric pressure in the feed device and the reservoir would be sufficient to enable the apparatus to operate.

95 Any odorant may be employed in practicing 45 this invention, that will be readily detected when the gas escapes and which can readily be incorporated into the flowing gas. For this purpose I prefer to use an odorant now sold on the market under the commercial name "Calodorant". A 50 liquid suitable for use as an odorant may include mercaptans, sulphides and disulphides. The odor is caused by the presence of the sulphur.

100 The general mode of operation of the apparatus will now be described. By reason of the 55 presence of the restricting means 3 in the pipe line, a differential of pressure is established between the pipe sections (1) before the restricting means, and (2) beyond the restricting means. The pressure in the section 1 of the line is maintained 60 through the pipe connections 8, 9, and 57, in the feed device 5 and in the reservoir 55. The odorant or other liquid being fed into the line passes by gravity from the elevated reservoir down the pipe 59 and through pipe 51 into the 65 interior of the feed device 5. The float 47 maintains a substantially constant level with the bath 7 in the feed device maintaining the level of the bath at about the level of line 15, which is above the outlet 13 on this feed device. The liquid 70 in the bath passes through the orifice disc 16 into the connection 18. This disc 16 offers opportunity for regulation of the flow from the feed device. By substituting a disc with a smaller orifice 17 the flow from the feed device can be 75

reduced, and vice versa. Any increase of pressure in the line section 1 causes an extension of the bellows 65, thereby opening the regulating valve 63 a greater amount to provide an increased flow of the liquid through its orifice 70. And this relieves the pressure in pipe 18, which loss of pressure is communicated to the bath 7 and the pressure chamber 6, causing an unbalance of the forces acting on the valve 46, and causing 10 this valve to open and give an increased flow of odorant. If the pressure drops this valve will restrict further the flow of the odorant. And as the operation of the device depends upon a differential of pressure, it is obvious that when 15 no differential pressure exists, as when no gas is flowing in the line, no odorant will be supplied to the line.

The flow of the odorant at all times can be observed at the sight feed 19, and, when desired, 20 by closing the valve 23, the odorant passing through the sight feed can be collected during a measured period of time to indicate the rate of movement of the odorant into the line. In the vaporizer at 30 the odorant or any other 25 liquid will become vaporized into a fog, which passes through the pipe connection 32 into the line at 33.

This apparatus can be employed for introducing a lubricant into the gas line to reduce the 30 frictional losses of the flow of the gas through a pipe system, and, if desired, the introduction of such a lubricant can be carried on simultaneously with the introduction of an odorant.

It is understood that the embodiment of the 35 invention described herein is only one of the many embodiments this invention may take, and I do not wish to be limited in the practice of the invention, nor in the claims, to the particular embodiment set forth.

40 **What I claim is:—**

1. In apparatus for injecting a liquid into a gas, the combination of a pipe line for conducting the gas, restricting means for restricting the flow of the gas at a point in the pipe line to 45 cause a differential of static pressure in the line before and beyond the location of the restricting means, a closed container for holding a quantity of the liquid, means for subjecting the surface of the liquid in the container to a pressure varying with the variations of the static pressure in the pipe line at a point before said restricting means and a connection from the container including regulating means for regulating the flow of the liquid, connected to the pipe line beyond 50 said restricting means, said regulating means including a pressure controlled compensator valve regulated by variations of the static pressure in the pipe line and having means for varying the effective valve opening to increase the flow of the liquid through the connection when the said static pressure rises.

2. In apparatus for injecting a liquid into a gas, the combination of a pipe line for conducting the gas, restricting means for restricting the flow of the gas at a point in the pipe line to cause a differential of static pressure in the line before and beyond the location of the restricting means, a closed reservoir for holding a supply bath of the liquid, a connection from the pipe line at a 55 point before the restricting means leading into the said reservoir for subjecting the surface of the liquid to the pipe line pressure, said reservoir having a feed outlet below the level of the bath, automatic valve-means for effecting a restricted feed of the liquid from the bath, a sight-feed

device for receiving the liquid fed forward from the bath and having its delivery opening located below the level of the bath in said reservoir, means for connecting the sight-feed device with the pipe line beyond said restricting means, and an automatic pressure-regulated compensating valve between the reservoir and the sight-feed device, said pressure-regulated valve having means controlled by the static pressure existing in said reservoir for regulating the effective valve opening through the compensating valve, and thereby affecting the flow through the first-named valve means. 10

3. In apparatus for injecting a liquid into a gas, the combination of a pipe line for conducting the gas, restricting means for restricting the flow of the gas at a point in the pipe line to cause a differential of static pressure in the line before and beyond the location of the restricting means, a closed reservoir for holding a supply bath of the liquid, a connection from the pipe line at a point before the restricting means leading into the said reservoir for subjecting the surface of the liquid to the pipe line pressure, said reservoir having a feed outlet below the level of the bath, a feed device with a chamber having a regulating bath therein and including a float-controlled valve for effecting a restricted feed of the liquid from the supply bath to the regulating bath, a sight-feed device for receiving the liquid fed forward from the regulating bath and having its delivery opening located at or about the level of the regulating bath in said feed device, means for connecting the sight-feed device with the pipe line beyond said restricting means, an automatic pressure-regulated valve between the reservoir and the sight-feed device, and having a pressure-controlled device controlled by the static pressure in the liquid from the regulating bath, and automatic means for maintaining a substantially constant surface level for said regulating bath. 25

4. In apparatus for injecting a liquid into a gas, the combination of a pipe line for conducting the gas, restricting means for restricting the flow of the gas at a point in the pipe line to cause a differential of static pressure in the line before and beyond the location of the restricting means, a closed reservoir for holding a supply bath of the liquid, a connection from the pipe line at a point before the restricting means leading into the said reservoir for subjecting the surface of the liquid to the pipe line pressure, said reservoir having a feed outlet below the level of the bath, valve means for effecting a restricted feed of the liquid from the bath, a sight-feed device for receiving the liquid fed forward from the bath and having its delivery opening located below the level of the bath in said reservoir, means for connecting the sight-feed device with the pipe line beyond said restricting means, said sight feed device having a collecting cup with a valve below the same to be closed at will for enabling the filling time of the cup to be observed. 50

5. In apparatus for injecting a liquid into a gas, the combination of a pipe line for conducting the gas under pressure above atmospheric pressure, restricting means for restricting the flow of the gas at a point in the pipe line to cause a differential of static pressure in the line before and beyond the location of the restricting means, a closed reservoir from which the atmosphere is excluded for holding a supply bath of the liquid, a connection from the pipe line at a point before the restricting means for leading gas into the reservoir for subjecting the upper surface of the 70 75

liquid to the pipe line pressure, said reservoir having a feed outlet below the level of the bath with a closed feed line leading to the pipe line beyond the restricted point, and a valve located 5 in the said feed line for effecting a restricted feed of the liquid from the bath into the feed line, and a float for closing the valve.

6. In apparatus for injecting a liquid into a gas, the combination of a pipe line for conducting 10 a gas at a pressure above atmospheric pressure, restricting means for restricting the flow of the gas at a point in the pipe line to cause a differential of static pressure in the line before and beyond the location of the restricting means, a 15 closed reservoir from which the atmosphere is excluded for holding a supply bath of the liquid, a connection from the pipe line at a point before the restricting means leading into the said reservoir for subjecting the surface of the liquid to 20 the pipe line pressure, said reservoir having a feed outlet below the level of the bath, a feed device having a regulating bath in the same supplied with liquid from the said reservoir and having a closed chamber above the level of the 25 liquid in the feed device communicating with the pipe line before the restricting means, said feed device having an inlet for admitting liquid from the supply bath, a valve controlling the same, and a float in the regulating bath of the feed 30 device for controlling the valve, and a connection between said regulating bath and the pipe line beyond the restricting means.

7. In a system for regulating the injection of liquid material into a gas stream, so that a substantially uniform concentration of said material in the gas is maintained, a combination of 35 means for injecting the liquid material, comprising: a differential pressure-producing means in the gas stream, means for discharging a liquid 40 stream into said gas stream, a differential pressure-responsive means in communication with the gas stream adapted to control the flow of the liquid in accordance with the velocity of the gas, and a static pressure-responsive means including 45 a valve in communication with the gas stream and capable of maintaining a predetermined mass ratio of the injected liquid to the gas.

8. In apparatus for injecting a liquid into a gas, the combination of a duct for the gas, restricting 50 means for restricting the flow of the gas at a point in the duct to cause a differential of static pressure in the duct before and beyond the location of the restricting means, a closed reservoir for holding a supply bath of the liquid elevated 55 above the duct, a connection from the duct at a point before the restricting means leading into the said reservoir for subjecting the horizontal upper surface of the liquid to the duct pressure,

said reservoir having a bottom feed-outlet considerably below the level of the bath; a closed casing, a valve seat within the casing, a float-controlled valve closing upon said valve seat against the pressure exerted by the liquid from 5 said supply bath, means for subjecting the interior of the casing and the back of the valve to static pressure of the duct, said valve operating to effect a restricted feed of the liquid from the supply bath, and means for connecting the 10 outlet from the valve to the duct beyond the said restricting means.

9. In apparatus for supplying a liquid to a gas line, the combination of a gas conduit through 15 which the gas flows, restricting means for restricting the flow of gas at a point in the said conduit, a closed reservoir for the liquid elevated above the conduit and having a bottom outlet with a closed delivery duct leading therefrom and connected to the conduit beyond the restricting 20 means, means for subjecting the horizontal upper surface of the supply liquid in the reservoir to substantially the same pressure as the gas in the gas conduit before the restricting means, valve means connected into the delivery 25 duct for shutting off flow of the liquid which flows by gravity from the reservoir, and for regulating the flow of the liquid therefrom to the said conduit, and means including a float actuated by differences in liquid level for controlling the 30 said valve through the agency of the differential pressure existing across the said restricting means.

10. The method of injecting a liquid odorant into a gas line carrying a gas flowing under a 35 pressure greater than atmospheric pressure, which consists in restricting the flow of gas in the pipe line to develop a differential pressure in the line before and beyond the restricted point, maintaining an elevated feed bath of the liquid 40 to be injected, above the gas line and from which the atmospheric pressure is excluded, subjecting the horizontal upper surface of the feed bath to the static pressure of the line before the restricted point, maintaining a supply reservoir 45 with a bottom opening at an elevation above that of the feed bath so that the liquid from the reservoir flows by the action of gravity down through the bottom opening to the feed bath, subjecting the horizontal upper surface of the liquid 50 in the reservoir to the static pressure of the line before the restricted point, supplying liquid from the said bath to the gas line beyond the restricted point, and varying the flow from the feed bath in accordance with variations in the 55 differential pressure.

FREDERIC A. HOUGH.
